E. G. Siggens.

ATTORNEY

UNITED STATES PATENT OFFICE.

TIMOTHY C. FOLEY, OF BENOVO, PENNSYLVANIA.

TOOL HOLDER.

Application filed April 18, 1922. Serial No. 554,676.

To all whom it may concern:

Be it known that I, TIMOTHY C. FOLEY, a citizen of the United States, residing at Renovo, in the county of Clinton and State of Pennsylvania, have invented new and useful Improvements in Tool Holders, of which the following is a specification.

This invention relates to tool holders for planers.

10 The object is to provide a device to be attached to planers for holding tools during the operation of planing a group or series of locomotive pedestal shoes, wedges or other parts used in connection with locomotive pedestals, or in other situations where rapidity and accuracy of work is desired.

15 The principal features of the invention are the provision of a suitable head for the reception of the various tools used in planing operations to afford facilities for the proper adjustment of the tools independently of each other with respect to the body of the tool holder; and to eliminate the resetting of the tool holder for different 20 operations.

25 The device is especially designed for use in conjunction with the improved planer chuck shown and described in a co-pending application, filed by me on September 16, 30 1920, Serial No. 410,659, which has matured into Patent No. 1,420,029, and of which the present application is a continuation in part.

35 In carrying out the invention, I provide a holder for planer tools which may be readily attached to the transversely adjustable planer head or heads movable crosswise of the bed of the machine, and carried forward during the planing process by the cross head of the same, to cause one or more 40 of the cutting tools carried thereby to act on the interior or exterior of said series of properly aligned parts held by the above-mentioned chuck, one of the interiorly acting tools being adjustable up or down in the holder to act as desired on the inside of 45 the walls of the wedges, and the exteriorly acting tools being laterally adjustable in the holder for a like purpose. The exterior tools are carried by swinging arms mounted in 50 the holder, said arms being rigidly held in vertical position, as viewed from the side, during the advancing movement of the car-

riage or cross head, and which, when the retrograde movement begins, are swung forwardly and outwardly from the work, so as 55 to free the tools therefrom during the entire return stroke or movement of the carriage.

A full and complete understanding of the invention may be obtained from a consideration of the following detailed description, 60 taken in connection with the accompanying drawings forming a part of this specification, it being understood that while the drawings show a practical form of the invention, the latter is not confined to strict 65 conformity with the showing thereof, but may be changed or modified, so long as such changes or modifications mark no material departure from the salient features of the 70 invention, as specifically pointed out in the appended claims.

In the drawings, in which similar reference characters designate corresponding parts throughout the several figures:

Fig. 1 is a front elevation of a portion of 75 a planer, showing the bed thereof supporting a double row of aligned work in position, the improved tool holders attached to the transversely adjustable heads being shown in operative relation to the same. 80

Fig. 2 is a side elevation of the subject matter of Fig. 1;

Fig. 3 is an enlarged, vertical sectional view of the tool holder, with the cutting tools therein; 85

Fig. 4 is a vertical sectional view, taken on the line 4—4 of Fig. 3;

Fig. 5 is a horizontal sectional view taken on line 5—5 of Fig. 3;

Fig. 6 is a vertical sectional view, taken 90 on the line 6—6 of Fig. 3;

Fig. 7 is a detail sectional view, taken on the line 7—7 of Fig. 3;

Fig. 8 is a detail view showing the position of the tools at the beginning of a cut 95 when planing the inside and outside walls of a shoe simultaneously;

Fig. 9 is a similar view showing the position of the tools at the finish of the planing operation. 100

In locomotive repair shops where it is necessary to reface or otherwise repair great quantities of locomotive pedestal shoes and wedge blocks of various forms, in order that

they may work smoothly and give satisfactory service, it is necessary to operate on a plurality of the same simultaneously in order to expedite the work, for these parts 5 must be returned to and replaced in operative position promptly to avoid tying up a locomotive too long.

Without the employment of a multiple work holding chuck of the type disclosed in 10 the aforesaid application, it is impossible to operate on a sufficient number of parts at one time, to facilitate said work, and the present improved tool holding device has been designed especially to be used in connection therewith to further expedite such work by providing for the simultaneous use 15 of opposed cutting tools to act on the exterior of such wedges, shoes or other parts, or for the use of only one of such tools, or 20 for the single or independent use of interiorly acting tools, which may also be used simultaneously with one or both of the exterior tools.

With these objects in view, the invention 25 consists in a tool holding block formed of a single steel casting, suitably formed and machined, to provide a vertically disposed, elongated body portion 1 having, somewhat below its central point, oppositely disposed 30 horizontal outstanding arms 2, integrally connected therewith and carrying, at their outer ends, integral, depending channel members 3, which are directed inwardly, at an angle to the body portion 1, and are 35 provided, in their front faces, with correspondingly inclined slots or channels 4 extending from top to bottom of said members 3 and located along the longitudinal axes of the same.

40 The body member 1 is provided, at its upper end, with opposed, outwardly extending arms 5, whose upper surfaces are flush with the top of the body member and said upper arms are provided with suitable apertures 45 for the reception of fastening bolts 6, while the lower arms 2 are likewise apertured for the reception of other fastening bolts 7, said bolts 6 and 7 being employed to secure the tool holder rigidly to the front 50 face of the usual planer heads 8 which are mounted for adjustment, transversely of the machine, upon suitable screws 9 carried in the cross head 10 of the planer.

55 The body member 1 is provided, in its rear face, with a longitudinally disposed, vertical slot 11, extending from top to bottom thereof, the said body member being slightly wider below the lower arms 2 than above the same, as clearly shown in Fig. 3 60 of the drawing, and the said slot 11 is extended forward in this widened portion of the body member, as indicated at 11^a in Fig. 6, to provide a seat for a tool 11^b of any of the usual forms. To the rear of this extended or deepened portion at the lower end 65

of the slot 11, a transversely disposed stiffening plate 13 is welded to the rear face of the lower end of the body member, below the lower edge of the planer head 8, said plate 13 being held against the rear edge of the tool 12 by means of the welding and bolts 14 traversing suitable aligned openings in the lower end of the body and the said plate. The inner ends of binding screws 15, which are threaded through the 70 front wall of the body and enter the slot 11, impinge against the front face of the tool 12 and bind the same against the front face of the planer head 8, said tool being employed for the purpose of planing the bottoms of shoes. 75 There is sufficient clearance between the tool 11^b and the tool 12, to allow adjustment of tool 12. The tool 11^b, which snugly fits the transverse slot 11^a, has suitable apertures for the passage of the bolts 14 which securely 80 hold the same in place.

85 Located in each inclined slot or channel 4 is a rocking, tool-carrying arm 16, formed of hardened steel and adapted to snugly fit said slot without any lost motion, the said 90 arm being pivoted at its upper end by means of a tapered pin 17 traversing the outer wall of the slot on an incline through a suitable inclined aperture in the upper end of the said arm, which is semi-circular 95 at its upper end as at 18, to permit the same to swing forwardly within said slot, the said pin 17 being seated into a suitable inclined aperture 19 beyond the channel 4 and communicating with a vertically disposed 100 bore 20 formed in the upper face of the arm 2, and into which is adapted to be driven a suitable tool for forcing the tapered and inclined pivotal pin 17 out of its frictional engagement in its seat, when it 105 is desired to change, repair or renew the arm 16 together with its tool-carrying means about to be described.

110 By reason of the inclined slots 4, the tool carrying arms 16 are inclined inwardly from their upper to their lower ends, and the mounting of the said inclined arms on the inclined pins enables them to swing up and away from the work on the return stroke of the planer.

115 The lower end of the arm 16 is provided with a rectangular head 21 having a transversely disposed passageway 22 for the reception of the shank of a horizontal disposed cutting tool 23 held in the desired lateral adjustment by means of suitable set screws 24 threaded through the front walls of the heads 21 and bearing against the tool in an obvious manner. The head is also provided with a vertically disposed aperture 25 into which may also be fitted a set screw to bear against the lower edge 120 of the tool 23.

125 By releasing the screws 15, the tool 12 may be lowered and positioned to cut the 130

proper amount from the bottoms or the interior walls or surfaces of the channel form of locomotive pedestal shoes, as indicated at 26 in Fig. 1 of the drawings, the said 5 shoes or wedges, as the case may be, being held in position by the improved planer chuck mechanism 27 heretofore referred to.

The tool 11^b, which may be used for planing the interior of both walls of the shoes 10 at the same time, is preferably widened at the lower end and provided with outwardly disposed cutting edges at the ends, the distance between the same being equal to the necessary distance between the said walls.

15 In like manner, the tools 23 may be adjusted to cut the desired amount from the exterior of the walls, etc., of the shoes 26 by releasing the screws 24, the finer adjustment of the same being accomplished by 20 means of the machine screws 9 in the usual manner.

When the cross head 10 of the planer is advancing in its operative movement, as indicated by the arrow in Fig. 2, the tools 23, 25 either singly or together, by reason of their contact with the work, are held firmly in the head of the arms 16 which find their seats in the bottom of the channels 4, and when the return movement of the cross head starts, 30 the said arms 16 swing upwardly automatically about their pivots and, by reason of the angular position of the latter, said tools are forced to move laterally and away from the work and not come into actual contact 35 with the same until the next forward movement. When it is desired to hold the arms 16 permanently out of the active position, a pin indicated in dotted lines at 28 may be inserted through an aperture 29 formed in 40 the outer wall of the channel member 3, said pin being adapted to extend into the channel and beneath the arm, when the latter is raised, as indicated in dotted lines in Fig. 4, so that the said arm is supported in elevated 45 position and the tool 23 is removed entirely from the work.

As indicated in Figures 8 and 9 the double-edged interiorly working tool 11^b may be employed to operate at the same time 50 with the swinging, exterior tools 23, the downward feed of said tools, necessary to act on a new surface, being accomplished through the usual, vertical feeding mechanism forming a part of the planer head 8 55 and not illustrated in the drawing.

From the foregoing it will be seen that a simple, cheaply manufactured tool holder has been provided which may be easily applied to an ordinary planer of sufficient capacity 60 for the purpose of operating on a plurality of locomotive pedestal shoes or wedges simultaneously, and that the tools may be adjusted to act on both exterior faces of the work at the same time, or one side at 65 a time, and that the said exterior tools may

be put out of action while a centrally disposed tool is employed for the purpose of planing the bottom of the work, or a double edged tool may be employed to plane both interior vertical faces of the shoe at the 70 same time.

What is claimed is:—

1. In a tool holder, the combination with the planer head, of a tool holding block formed of a single casting, means provided 75 in said block for holding a tool in a vertical position with its lower cutting end projecting below the said block, and a pair of arms formed on said block and provided with horizontally disposed tool holding means 80 carrying tools which have their cutting edges projecting inwardly toward the other tool.

2. In a tool holder, the combination with the planer head, of a tool holding block 85 formed of a single casting, means provided in said block for holding a tool in a vertical position with its lower cutting end projecting below the said block, means also provided in said block for holding a double-edged tool in advance of the first-mentioned tool, and a pair of arms formed on said block and provided with horizontally disposed tool holding means carrying tools 90 which have their cutting edges projecting inwardly toward the other tools.

3. In a tool holder, the combination with a body portion having means for holding a tool in substantially the vertical center thereof, and projecting downwardly from 100 the body portion, and a pair of swingable arms carried by the body portion, one at each side thereof, each arm having a horizontally disposed tool holder at the lower end, said arms being constructed and mounted so as to rise automatically from the work on the return movement thereof.

4. In a tool holder, the combination with the planer head, of a tool holding block 110 formed of a single piece of metal and provided with a longitudinally disposed slot extending from top to bottom and adapted to receive a tool with its cutting end projecting from the bottom, means for holding a centrally disposed tool having opposite, vertical cutting edges directed outwardly, fixed arms extending outwardly from each side of said slot and provided with depending channel members, and arms in the channels of said members and carrying tool holders at 115 their lower ends.

5. In a tool holder, the combination with a planer head, of an elongated body portion having means for holding a transversely-disposed tool having a cutting edge at each end, a pair of arms pivoted to the body portion at each side thereof and carrying tool holders at their lower ends, with the tools arranged in a substantially horizontal position and at each side of the first-mentioned 125 130

tool, said arms being adapted to be swung upwardly into an inactive position, and means for holding said arms when raised.

6. In a tool holder, the combination with a planer head, of an elongated body portion having means for holding a substantially vertically disposed tool at the vertical center thereof, with the lower end of the tool projecting below the body portion, means for holding a transversely-disposed tool having a cutting edge at each end, a pair of arms pivoted to the body portion at each side thereof and carrying tool holders at their lower ends, with the tools arranged in a substantially horizontal position and at each side of the first-mentioned tool, said arms being adapted to be swung upwardly into an inactive position, and means for holding said arms when raised.

10. 7. In a tool holder, the combination with the planer head, a tool holding block formed of a single casting, and comprising an elongated body portion with oppositely disposed outstanding arms, said body portion having means to receive and hold a tool which projects at its cutting end below the bottom of said body portion, said arms having depending channel members provided with inwardly converging channels, swingable arms mounted in said channels, inclined pins for pivoting the arms in said channels, and tool holding means carried by the lower ends of said arms to receive tools.

15. 8. In a tool holder, the combination with a planer head, of a tool holding block formed of a single casting, consisting of a vertically disposed elongated body portion having a channel on its inner side to receive a vertically disposed tool, with the lower end of the tool projecting below the body portion, and outstanding arms provided with depending channel members having inwardly inclined channels extending from top to bottom thereof, swingable arms mounted in said channels and partaking of the inclination thereof, tool holding means carried by the lower ends of said arms, and inclined pins for pivoting the upper ends of said swingable arms in said channels.

20. 9. In a tool holder, the combination with the planer head of a machine for planing locomotive pedestal shoes, of a tool holding block formed of a single casting, consisting of a vertically disposed elongated body portion having a channel on its inner side to receive a vertically disposed tool, with the lower end of the tool projecting below the body portion, said body member having a transverse slot provided in its lower end, a cutting blade adapted to seat in said slot and having a cutting edge at each end adapted to act on the inner faces of the vertical walls of the shoes, bolts for holding the blade in the slot, and outstanding arms provided with depending channel members having inward-

ly inclined channels extending from top to bottom thereof, swingable arms mounted in said channels and partaking of the inclination thereof, tool holding means carried by the lower ends of said arms, and inclined pins for pivoting the upper ends of said swingable arms in said channels.

25. 10. A tool holder adapted to be attached to the planer head of a planing machine, comprising a body member having a centrally disposed substantially vertical tool-receiving slot, means for clamping a tool therein against the face of the planer head for operating on the bottom walls of work, means for holding a transverse tool having a vertical cutting edge at each end, for planing the interior walls, outstanding arms carried by the body member, terminating in downwardly and inwardly directed channel members arranged at each side of the central tool and adapted to straddle work secured to the bed of the planer, said members having inclined channels formed therein, tool-carrying arms pivoted at their upper ends in the inclined channels and provided with transverse tool heads at their lower ends adapted to carry inwardly directed, opposed tools for operating on the exterior of the work.

30. 11. A tool holder for planers comprising a body member adapted to be bolted to the head of the planer, said body member being arranged vertically on said head and provided with a vertical slot in its rear face for the reception of a tool for operating on the bottom interior walls of work secured to the bed of the planer, means for clamping the tool against the head of the planer, a seat formed in the lower end of the body transversely thereof for the reception of a plate having opposed, vertical cutting edges at its ends, means for holding the plate in the slot, lateral extensions carried by the body member and terminating in downwardly converging channel members provided in their front faces with inclined channels, arms pivotally mounted at their upper ends in the upper ends of the channels and having heads at their lower ends in alignment with the said work and adapted to carry inwardly-directed tools to act on the exterior walls of the work in the forward movement of the planer head and to drag inactively on the retrograde movement thereof, or to be swung upwardly and outwardly to inactive position when desired.

35. 12. A tool holder for planers comprising a body member adapted to be bolted to the head of the planer, said body member being arranged vertically on said head, lateral extensions carried by the body member and terminating in downwardly converging channel members provided in their front faces with inclined channels, arms pivotally mounted at their upper ends in the upper

ends of the channels and having heads at their lower ends in alinement with the said work and adapted to carry inwardly-directed tools to act on the exterior walls of the work 5 in the forward movement of the planer head and to drag inactively on the retrograde movement thereof, or to be swung upwardly and outwardly to inactive position when desired.

- 10 13. In a tool holder, the combination with a planer head, of a body portion, means for holding a transversely disposed tool with a cutting edge at each end at the bottom of said body portion, a pair of arms pivoted to 15 the body portion at each side thereof and carrying tool holders at their lower ends, with the tools arranged in a substantially horizontal position and on each side of the first-mentioned tool, whereby the first-men-

tioned tool is adapted to cut the inside of a 20 shoe while the other tools operate on the outside thereof and both simultaneously.

14. In a tool holder, the combination with a planer head, of a body portion carried thereby having means for holding a transversely disposed tool with a cutting edge at each end in a position at the bottom of the body portion, and other means located at each side of said tool and carrying tool holders at their lower ends with the two tools arranged in a substantially horizontal position, whereby the three tools are adapted to operate simultaneously on the inside and outside respectively of a shoe.

In testimony that I claim the foregoing as my own, I have hereto affixed my signature.

TIMOTHY C. FOLEY.
